HIS ATTORNEYS.

UNITED STATES PATENT OFFICE

HARRY W. KRAG, OF ST. LOUIS, MISSOURI, ASSIGNOR TO AMERICAN SHOE MACHINERY
AND TOOL COMPANY, OF ST. LOUIS, MISSOURI, A CORPORATION OF MISSOURI

CHANNEL CUTTING PRESSER FOOT

Application filed September 8, 1931. Serial No. 561,557.

This invention relates to presser feet for shoe sole sewing machines, particularly presser feet of the kind provided with means for cutting a thread receiving channel in the shoe sole in advance of the needle. The principal object of the present invention is to provide a channel cutting presser foot with simple and efficient means for adjusting the channel cutter to bring it in line with the needle and to vary the depth of cut. Another object is to provide means for readily securing the channel cutter in the desired adjusted position. Other objects are simplicity, economy and compactness of design. The invention consists in the channel cutting presser foot and in the construction, combinations and arrangements of parts hereinafter described and claimed.

In the accompanying drawing, which forms part of this specification and wherein like symbols refer to like parts wherever they occur.

Fig. 1 is a plan view of a channel cutting presser foot embodying my invention,

Fig. 2 is a front elevation thereof,

Fig. 3 is a side view of said presser foot,

Fig. 4 is a bottom plan view of said presser foot,

Fig. 5 is a cross-section on the line 5—5 in Fig. 2; and

Fig. 6 is a cross-section on the line 6—6 in Fig. 2.

Referring to the accompanying drawing, my channel cutting presser foot comprises a shank portion 1 which is adapted to be secured, preferably by means of cap screws 2, to the free end of the presser foot lever (not shown) of a shoe sole sewing machine. The shank portion 1 of the presser foot is provided at its lower or outer end with an enlarged body portion 3 having a presser foot portion 4 that projects horizontally from one side thereof for pressing the shoe sole against the work support (not shown) of the sewing machine.

Slidably mounted in an inclined rectangular groove provided therefor in the front face of the enlarged body portion 3 of the presser foot is a cutter 6, one end of which extends

thread receiving channel in the shoe sole (not shown) in advance of the needle 7. As shown in the drawing, said channel cutter 6 comprises a triangular bar that is disposed longitudinally of the groove 5 with one of its faces disposed flatwise against the top wall of said groove and with its lower edge disposed adjacent to the bottom wall thereof.

The triangular channel cutter 6 is clamped in the groove 5 by means of a clamping member, which comprises a cylindrical shank portion 8, having a cross-flange or head 9 at its lower end. The clamping member is mounted on the presser foot with its shank portion 8 slidably engaging a bore 10 that extends through the enlarged body portion 3 of said presser foot back of and at right angles to the cutter receiving groove 5 and with its cross-head or flange 9 disposed crosswise of said groove and forming the rear end portion of the bottom wall thereof. The clamping member is forced upwardly to force the cross-flange 9 thereof against the bottom edge of the channel cutter to clamp the top face of said cutter against the top wall of the groove 5 by means of a screw 11 mounted in a screwthreaded opening 12 provided therefor in the front face of the enlarged portion 3 of the presser foot above the groove 5 therein. The inner end of this screw receiving opening 12 communicates with the bore 10 that slidably receives the shank portion 8 of the clamping member; and the screw 11 is provided with a conical or tapered inner end portion 13 adapted to enter a conical recess 14 provided therefor in the side of said shank portion. By this arrangement, when the screw 11 is tightened the conical inner end portion 13 thereof is forced against the conical surface of the recess 14 in the shank portion 8 of the clamping member thereby causing said member to travel upwardly. This upward travel of the clamping member causes the cross-flange 9 thereof to press upwardly against the lower edge of the channel cutter 6 and thus firmly clamp the flat upper face thereof against the top wall of the groove 5 therefor. As shown in the drawing, the cross-flange 9 of the clamping member is provided with a channel 15 having a

flat surface at its bottom adapted to permit a slight side play of said edge of said cutter therein.

The channel cutter 6 is adjusted horizontally in a direction transverse to its length by means of an adjusting screw 16, which is threaded in an opening 17 provided therefor in the front face of the body portion 3 of the presser foot adjacent to the front end portion 10 of the top wall of the cutter receiving groove 5, the screw receiving opening 17 opens into the groove 5 through the top wall thereof; and the adjusting screw 16 is provided with an annular groove 18 adapted to 15 receive the flat upper face of the channel cutter 6 located in the groove 5. By this arrangement, manipulation of the screw 16 causes the same to move in the direction of its axis, which movement, by reason of the 20 engagement between the annular groove 18 in said screw with the channel cutter 6, causes said channel cutter to be shifted in a direction transverse to its length. As stated above, the crosswise movement of the rear end portion 25 of the channel cutter 6 is restricted by means of the channel 15 in the cross-flange 9 of the clamping member, thus causing the rear end portion of said cutter to remain in said channel while permitting a greater 30 amount of crosswise movement of said cutter at the forward end thereof. In practice, a slight clearance is provided between the channel cutter and the side walls of the annular groove in the adjusting screw 16 in 35 order to prevent binding of said cutter in said groove when the movement of the forward end of said cutter is greater than the movement of the rear end thereof. The pressure of the adjusting screw 16 on the channel 40 cutter is sufficient to overcome the friction between the top face of said channel cutter and the top wall of the groove therefor, thereby permitting crosswise adjustment of the cutter without releasing the clamping member. 45 However, when it is desired to adjust the channel cutter in the direction of its length, it is necessary to release the clamping member by loosening the screw 11 which presses the cross-flange of said clamping 50 member against the bottom edge of said channel cutter.

What I claim is:

1. A channel cutting presser foot having a plane surface, a channel cutter having a 55 plane surface cooperating with the plane surface of said presser foot, means on said presser foot cooperating directly with said channel cutter for moving the same transversely of its length, and means on said 60 presser foot for clamping the plane surface of said channel cutter against the plane surface of said presser foot.

2. A channel cutting presser foot having a plane surface, a channel cutter having a 65 plane surface cooperating with the plane

surface of said presser foot, means on said presser foot cooperating with said channel cutter for moving the same transversely of its length, and means on said presser foot for clamping the plane surface of said channel cutter against the plane surface of said presser foot, said clamping means comprising a member having a shank portion mounted in said presser foot for sliding movement transversely of said channel cutter and having a portion adapted to bear against said channel cutter to press the plane surface of the latter against the plane surface of said presser foot.

3. A channel cutting presser foot having a plane surface, a channel cutter comprising a triangular bar mounted on said presser foot with one of its faces cooperating with said plane surface, a screw threaded into said presser foot substantially at right angles to said triangular bar and having an annular groove adapted to straddle said bar, and a member having a shank portion mounted in said presser for sliding movement transversely of said bar and said screw and having a flange adapted to bear against said bar to clamp said face thereof against the plane surface of said presser foot.

4. A channel cutting presser foot having a plane surface, a channel cutter comprising a triangular bar mounted on said presser foot with one of its faces cooperating with said plane surface, a screw threaded into said presser foot substantially at right angles to said triangular bar and having an annular groove adapted to straddle said bar, and a member having a shank portion mounted in said presser for sliding movement transversely of said bar and said screw and having a flange adapted to bear against said bar to clamp said face thereof against the plane surface of said presser foot, said shank portion of said clamping member being provided with a tapered recess, and a screw threaded in said presser foot at right angles to said shank portion and having a tapered end portion adapted to cooperate with said tapered recess.

5. A channel cutting presser foot having a plane surface, a channel cutter comprising a triangular bar mounted on said presser foot with one of its faces cooperating with said plane surface, a screw threaded into said presser foot substantially at right angles to said triangular bar and having an annular groove adapted to straddle said bar near the cutting end thereof, a member having a shank portion mounted in said presser for sliding movement transversely of said bar and said screw and having a flange adapted to bear against said bar to clamp said face thereof against the plane surface of said presser foot, said shank portion of said clamping member being provided with a tapered recess, and a screw threaded in said presser foot at right angles to said shank portion and having a ta-

pered end portion adapted to cooperate with said tapered recess, the bar engaging portion of said flange of said clamp member comprising a channel formed in said flange and shaped to permit limited side play of the portion of said bar cooperating therewith.

5 6. A channel cutting presser foot having a groove therein, a channel cutter slidable in said groove, and means on said presser foot 10 cooperating directly with said channel cutter for moving the same transversely of said groove.

15 7. A channel cutting presser foot having a groove therein, a channel cutter slidable in said groove, means on said presser foot cooperating with said channel cutter for moving the same transversely of said groove, said means comprising a screw threaded into said presser foot transversely of said channel cutter and having an annular groove adapted to straddle said channel cutter and means on 20 said presser foot for clamping said channel cutter in said groove.

25 8. A channel cutting presser foot having a groove therein, a channel cutter slidable in said groove, means on said presser foot cooperating with said channel cutter for moving the same transversely of said groove, and means on said presser foot for clamping said 30 channel cutter in said groove, said clamping means comprising a member having a shank portion mounted in said presser foot for sliding movement transversely of said channel cutter and having a flange adapted to bear 35 against said channel cutter to force the latter against one wall of said groove.

40 9. A channel cutting presser foot having a groove therein, a channel cutter slidable in said groove, means on said presser foot cooperating with said channel cutter for moving the same transversely of said groove, means on said presser foot for clamping said channel cutter in said groove, said clamping means comprising a member having a shank 45 portion mounted in said presser foot for sliding movement transversely of said channel cutter and having a flange adapted to bear against said channel cutter to force the latter against one wall of said presser foot, said shank portion of said clamping member being provided with a tapered recess, and a screw threaded in said presser foot at right angles to the shank portion of said clamping member and having a tapered end portion 50 adapted to cooperate with the tapered recess formed in the shank portion of said clamping member.

55 10. A channel cutting presser foot having a groove in the front face thereof, a channel cutter slidable in said groove, and means on said presser foot cooperating with said channel cutter for moving the same transversely of said groove, said means comprising a screw threaded into said presser foot substantially at right angles to said channel cut-

ter and having an annular groove formed therein adapted to straddle said channel cutter.

11. A channel cutter presser foot having a groove therein, a channel cutter slidable in 70 said groove, means on said presser foot cooperating with said channel cutter for moving the same transversely of said groove, said means comprising a screw threaded into said presser foot substantially at right angles to 75 said channel cutter and having an annular groove formed therein adapted to straddle said channel cutter, and means for clamping said channel cutter in said groove, said clamp- 80 means comprising a clamping member having a shank portion slidable in said presser foot at right angles to said channel cutter and to said screw and having a crosshead extending beneath said channel cutter in directions transverse thereto, said shank portion of said clamping member being provided with a tapered recess, and an adjusting screw 85 threaded into said presser foot at right angles to said shank portion and having a tapered end portion adapted to engage the tapered 90 recess therein.

Signed at St. Louis, Missouri, this 4th day of September, 1931.
